UNITED STATES PATENT OFFICE.

CHARLES W. HUBBARD, JR., OF NEW YORK, N. Y.

CIGARETTE-BOX.

1,152,815.

Specification of Letters Patent.

Patented Sept. 7, 1915.

Application filed October 24, 1914. Serial No. 868,354.

To all whom it may concern:

Be it known that I, CHARLES W. HUBBARD, Jr., a citizen of the United States, and resident of the borough of Manhattan, in the city, county, and State of New York, have invented certain new and useful Improvements in Cigarette-Boxes, of which the following is a specification.

The object of this invention is to provide a simple and practicable box in which cigarettes may be sold to the consumer, having the attractive appearance and convenience of the carrying cases of more expensive materials to which cigarettes are commonly transferred from the original package. Otherwise stated, the object is to enable a receptacle on the order of a cigarette case to be made of comparatively cheap and perishable materials suitable for the retail package, so that it may serve the purposes of both, to insure the cigarettes being safely guarded and held, and to admit of their individual removal safely and without spilling. These ends are attained by a combination of outer receptacle, consisting of box halves formed of dished cardboard blanks, with an elastic retaining band and an inner pocket or folder beneath the band, whereby the cigarettes are securely held and perfectly protected without the necessity of dishing the box parts deeply or of providing fastening means, thereby simplifying the manufacture, avoiding breakage of the cardboard stock, and ultimately facilitating the extraction of the cigarettes, and whereby, also, bending of the cigarettes by the hand, while being held or in the act of removal, is avoided.

Further features and advantages will be apparent to those skilled in the art from the specification and drawing.

In the said drawings: Figure 1 is a perspective view of the box closed, its halves being held together by a revenue stamp or paster; Fig. 2 is a view of the box opened, portions being broken away; Fig. 3 is a section on the line 3—3 of Fig. 2; Fig. 4 is a view partially in side elevation and partially in longitudinal section through the box; and Fig. 5 is a fragmentary view showing one of the cigarettes partially withdrawn.

The box comprises two oblong halves 2 and 3, of suitable cardboard stock, united at two of their short sides by a hinge 4, preferably consisting of a piece of textile fabric glued or pasted to both halves. These box

members consist of single blanks formed in dies, so as to have imparted thereto a gentle curvature 5 at the four sides, the shallowness of the dishing avoiding injury to the stock. The blanks are intended to be covered outside with a suitable finishing paper, and the edges of the members are preferably formed as flat, outwardly-directed rims 12 constituting desirable bearing surfaces 65 and improving the appearance of the box. The member 3, which may be termed the bottom member, bears an elastic retaining band 6, stretched lengthwise across its interior, at right angles to the line of the hinge, 70 the ends of this band being inturned and embedded in and pasted to the material of the sloping portion of the box member, and covered by a finishing sheet 7, as more particularly set forth in my co-pending applications Serial Number 833,424, filed April 21, 1914, and Serial Number 833,425, filed April 21, 1914. Beneath the band is a folder 8, forming a pocket in which the cigarettes are held in a single row. The said folder 75 preferably consists of a sheet of heavy foil with a lining of paper, which are folded on two lines to form a back 9, a bottom and inner flap 10, and an upper and outer flap 11. The bottom flap is interposed between the 80 band and the cigarettes, and is thus held in place by the former and serves as a guard for the latter to prevent them being bent by the band. The upper flap overlies the band and may be readily turned up to expose the 85 ends of the cigarettes. In order to prevent displacement, the back of the folder pocket is preferably glued to the bottom of the box member. It will be observed that the efficiency of the folder as a pocket is due to the 90 co-operation therewith of the elastic band, and that this mode of holding the cigarettes between the box halves renders it unnecessary to dish the box members deeply and thereby secures the advantages as to manufacture and use already indicated. The 95 cigarettes are slid outward in almost a straight line, which is not only convenient but also insures their removal in good condition, the operation being further facilitated by the fact that the upper flap 11 folded backward affords an easy sliding surface to guide the end of the cigarette over the curve of the box. A further advantage of the inner pocket in which the cigarettes are held is that a catch for the box 100 halves is rendered unnecessary, and thus a 105

110

serious item of expense and a considerable manufacturing difficulty are avoided. Previous to sale, the box may be held closed by the revenue stamp or by a paster. In addition, the pocket insures the cigarettes being kept in a fresh condition and adequately protects them, even though the edges of the box halves do not come together closely. In the drawings the edges are shown meeting 10 on a straight line, but in actual practice they are likely to be separated to a certain extent and may be more or less uneven, without detracting from the effectiveness or appearance of the package. As indicated in 15 Figs. 2 and 5, an important function of the foil pocket is to conform to the number of cigarettes remaining at any one time, clasping them in such a way that it is practically impossible for them to fall out or become 20 displaced.

What I claim as new is:

1. A package for cigarettes, comprising an outer receptacle consisting of oblong dished box-halves joined by a hinge at one 25 of the short ends and adapted to receive the cigarettes in a single row, in combination with an elastic retaining band secured lengthwise across the interior of one of the

box-halves, and a folder pocket beneath said band, said pocket comprising a back overlying the bottom of said box-half, a lower flap continuous with said back and carried up over the cigarettes from their lower ends and held by said retaining band, and an upper flap continuous with the back and covering the upper portions of the cigarettes and adapted to permit the removal of the same. 30

2. A package for cigarettes, comprising an outer receptacle consisting of hinged box 40 halves, each consisting of a single piece of dished cardboard stock, in combination with an elastic retaining band secured across one of the box halves, and a folder comprising a back applied to the bottom of said box 45 half, a lower and inner flap interposed between the band and the cigarettes, and an upper and outer flap adapted to be turned back to expose the ends of the cigarettes.

In testimony whereof I have signed my 50 name in the presence of two witnesses.

CHARLES W. HUBBARD, JR.
